UNITED STATES PATENT OFFICE.

WALTER V. TURNER, OF EDGEWOOD, PENNSYLVANIA, ASSIGNOR TO THE WESTINGHOUSE AIR BRAKE COMPANY, OF PITTSBURGH, PENNSYLVANIA, A CORPORATION OF PENNSYLVANIA.

TRIPLE-VALVE DEVICE.

1,119,899.

Specification of Letters Patent.

Patented Dec. 8, 1914.

Application filed January 5, 1909. Serial No. 470,791.

To all whom it may concern:

Be it known that I, WALTER V. TURNER, a citizen of the United States, residing at Edgewood, in the county of Allegheny and 5 State of Pennsylvania, have invented new and useful Improvements in Triple-Valve Devices, of which the following is a specification.

This invention relates to fluid pressure 10 brakes, and more particularly to a triple valve device of the type in which air is locally vented from the train pipe in applying the brakes for the purpose of accelerating the serial action of the brakes.

15 One object of my improvements is to provide an improved triple valve device of the above character in which the local train pipe vent port is controlled directly by the triple valve piston and valve, thus doing 20 away with the usual emergency valve mechanism.

Another feature of my invention contemplates utilizing the same train pipe vent port for locally reducing the train pipe 25 pressure both in service and emergency applications of the brakes.

In the accompanying drawings; Figure 1 30 is a central sectional view of a triple valve device with my improvements applied thereto, showing the parts in normal full release position; Fig. 2 a similar view, but with the parts shown in service application position; Fig. 3 a like view, showing the parts in 35 emergency application position; Fig. 4 a face view of the main slide valve of the triple valve, showing the ports therein and their relative location; and Fig. 5 a plan view of the valve seat for the main slide valve.

40 To illustrate an application of my improvements the drawings show a triple valve device comprising a casing 1 having piston chamber 2 containing triple valve piston 3 and valve chamber 4 containing the main 45 slide valve 5 and the auxiliary or graduating valve 6 mounted on and having the usual movement relative to the main slide valve. The train pipe passage 7 opens into piston chamber 2 and the usual feed groove 50 8 establishes communication from the train pipe to the auxiliary reservoir when the triple piston is in release position. In the present construction, in addition to the usual normal release position, the triple valve parts

are adapted to assume an inner position, in 55 which the piston 3 seats and cuts off communication from the valve chamber 4 to the auxiliary reservoir, the auxiliary reservoir being open to said valve chamber only by way of the passage 9 which leads to the 60 space at the inner face of piston 3. Means are provided tending to return the triple valve parts from this inner position to the normal release position, such as a coil spring 10 and a movable member 11 subject to the 65 pressure of the spring and adapted to bear on the piston stem 12.

The main slide valve is provided with the usual service port 13 controlled by the auxiliary valve 6 and adapted to register in 70 service application position with brake cylinder port 14, exhaust cavity 15 adapted to connect brake cylinder port 14 with exhaust port 16 in release position of the parts, and emergency port 17. According to my im- 75 provements, the train pipe vent port 18 leads to the seat of the main slide valve 5, said port being provided with the usual check valve 19 to prevent back flow through the vent port 18 from the auxiliary reservoir. 80 The auxiliary reservoir is charged from train pipe through the feed groove 8 in the usual manner, the groove being open in both the normal release position and the extreme inner position of the parts. 85

A gradual reduction in train pipe pressure shifts the triple valve parts to service position as shown in Fig. 2, in which the service port 13 is uncovered by the graduating valve 6 and air is supplied from the 90 auxiliary reservoir to the brake cylinder. According to one feature of my improvements I provide ports 21 and 22 in the main slide valve and a cavity 23 in the graduating valve 6, which is adapted to connect the 95 ports 21 and 22 in the outward movement of the parts to service position. In service position port 21 registers with vent port 18 and port 22 registers with a prot 24 leading in the present instance to a small expansion 100 chamber 25. Air then flows from the train pipe to the small expansion chamber until the pressure in the chamber equalizes with that in the train pipe or the triple valve parts move to lap position, in which port 22 105 is closed. As shown in the drawings, the port 22 may have a restricted portion 26 to limit the rate of flow of air from the train

2

pipe or the port may be full size the capacity of chamber 25 being so limited that the train pipe pressure will not be reduced sufficiently to cause movement of the triple valve parts to emergency position. When the auxiliary reservoir pressure has reduced by flow to the brake cylinder to that in the train pipe the triple valve piston shifts the auxiliary valve 6 to lap position closing the service port and the local train pipe vent port. A restricted port 28 leads from the chamber 25 to the brake cylinder passage 14 and the brake cylinder, through which the pressure in the chamber gradually equalizes with that in the brake cylinder, so that if a successive reduction in train pipe pressure is made, a further local venting of air from the train pipe is produced, though less in amount, according to the degree of pressure in the brake cylinder. The local venting of the train pipe is consequently repeated on successive service applications until the point of full equalization is reached. Upon a sudden reduction in train pipe pressure, the triple valve parts move out to emergency position, the triple valve piston seating on the emergency gasket in the usual manner. Emergency port 17 now registers with brake cylinder port 14 and air from the auxiliary reservoir flows to the brake cylinder. As shown in Fig. 3 port openings of a large port 27 in the main slide valve registers in emergency position with the train pipe vent port 18 and the port 31 leading to a larger expansion chamber 35 whereby a rapid reduction in train pipe pressure is made according to the capacity of the expansion chamber 35 thereby causing quick action of all the triple valves in the well known manner.

In order to relieve the emergency expansion chamber of pressure in releasing the brakes after an emergency application, a restricted port 33 may be provided in the wall 32 which separates the expansion chamber 35 from chamber 25, so that the fluid contained in said chamber may flow to chamber 25 and thence by port 28 to the brake cylinder passage 14 and thence to the atmosphere.

In releasing the brakes after either a service or an emergency application of the brakes, the increase in train pipe pressure shifts the parts to the normal full release position or to the inner position in which the spring 10 is compressed, according to the rate of increase in train pipe pressure. In the inner position of the parts, port 20 registers with the train pipe vent port 18, and piston 3 seats so as to cut off communication from the auxiliary reservoir to the valve chamber 4, so that while the valve chamber is open to the train pipe through the vent port 18, the small capacity of said chamber prevents flow of air from the train pipe to

such an extent as to interfere with the quick serial release of the brakes, such as would be the case were the train pipe open through the large train pipe vent port to the auxiliary reservoir. In the meantime, the auxiliary reservoir is recharged through the usual feed groove around the triple valve piston and upon substantial equalization of pressures on the opposite sides of the piston, the spring 10 shifts the parts to the normal full release position. In this normal position, it will be noted that vent port 18 is closed, so that there is no possibility of the triple valve failing to move to application position, as might occur in case of a leaky check valve where the vent port is open to the valve chamber and auxiliary reservoir, by reason of the back flow of air from the auxiliary reservoir to the train pipe through the large vent port.

My improvements are particularly well adapted to be employed in connection with triple valve devices in which means are provided for securing a more simultaneously release of the brakes throughout the train, and known as the retarded release feature, such construction having a normal full release and an inner position, in which the passage through which air is released from the brake cylinder is restricted, and having means tending to move the parts from the inner position to the normal full release position, such as, for example, the construction covered in Patent No. 920,504 of W. V. Turner, dated May 4, 1909. As shown in the present drawings, this so-called retarded release feature is brought about by so arranging the exhaust cavity 15 in the main slide valve as to either entirely close or restrict the communication through which air is released from the brake cylinder, by providing cavity 15 with restricted port extension 29 adapted in the inner or retarded release position to register with exhaust port 16, so that the flow of air from the brake cylinder is restricted.

With the present improvements, it will now be apparent that the local train pipe vent port may be readily controlled by the main valve of the triple valve device without danger of blowing the valve from its seat or liability of leakage past the emergency check valve interfering with the positive movement of the parts in applying the brakes, as in the normal release position, the local vent passage is closed by the main slide valve.

In some cases the vent chambers may be dispensed with and the local venting of train pipe air may be to the brake cylinder, the atmosphere, or elsewhere, as desired.

Having now described my invention, what I claim as new and desire to secure by Letters Patent, is:—

1. A triple valve device comprising a mov- 130

able abutment subject to the opposing pressures of the train pipe and auxiliary reservoir and a valve operated by said abutment for controlling a local train pipe vent port and having a normal release position in which said train pipe vent port is closed and an inner position in which communication is open through said vent port.

2. A triple valve device comprising a casting having a valve chamber, a valve in said chamber for controlling the release of air from the brake cylinder and a local train pipe vent port, a movable abutment subject to the opposing pressures of the train pipe and auxiliary reservoir for operating said valve, the valve and piston having a normal release position in which the train pipe vent port is closed and an inner position in which said vent port is open to the valve chamber.

3. In a fluid pressure brake, the combination with a train pipe, auxiliary reservoir, and brake cylinder, of a valve for controlling the exhaust from the brake cylinder and a train pipe vent port, and a movable abutment for operating said valve and subject to the opposing pressures of the train pipe and a chamber, normally open to the auxiliary reservoir, and having an inner position in which the chamber is cut off from the auxiliary reservoir and in which said valve opens the train pipe vent port to said chamber.

4. In a fluid pressure brake, the combination with a train pipe, auxiliary reservoir, and brake cylinder, of a triple valve device comprising a movable abutment subject to the opposing pressures of the train pipe and auxiliary reservoir, valve means operated by said abutment for venting air from the train pipe in applying the brakes, and means for closing communication from the auxiliary reservoir to said valve chamber and for opening communication from train pipe to the valve chamber upon an increase in train pipe pressure.

5. A triple valve device comprising a movable abutment subject to the opposing pressures of the train pipe and auxiliary reservoir, a valve operated by said abutment upon a reduction in train pipe pressure for venting air from the train pipe and upon an increase in train pipe pressure for opening communication from the train pipe to the valve chamber, and means for closing communication from the auxiliary reservoir to said chamber.

6. A triple valve device comprising a movable abutment and valve having a normal release position in which the valve chamber is open to the auxiliary reservoir and an inner position in which said chamber is cut off from the auxiliary reservoir, said valve having means for opening a local train pipe vent port upon a reduction in train pipe pressure to apply the brakes and

for opening communication from said vent port to the valve chamber upon an increase in train pipe pressure to release the brakes.

7. A triple valve device comprising valve means for controlling the brake cylinder supply port and a local train pipe vent port, a movable abutment subject to the opposing pressures of the train pipe and auxiliary reservoir for operating said valve means, said valve means having ports for opening said train pipe vent port in service and emergency applications of the brakes and adapted to open said vent port in a position for releasing the brakes.

8. A triple valve device comprising a piston and valve means operated by said piston upon a gradual reduction in train pipe pressure to effect a service application of the brakes and upon a sudden reduction in train pipe pressure to effect an emergency application of the brakes and having a local train pipe vent port adapted to be opened for venting fluid from the train pipe in service and emergency application positions of said valve means and also in a release position 90 to the valve chamber containing said valve means.

9. A triple valve device comprising a movable abutment subject to the opposing pressures of the train pipe and auxiliary reservoir, and valve means operated by said abutment and having ports adapted to open a local train pipe vent port in service and emergency application positions and a port for connecting said local vent port to the valve chamber in a position for releasing the brakes.

10. A triple valve device having a valve chamber and comprising a movable abutment subject to the opposing pressures of the train pipe and auxiliary reservoir, and valve means contained in said valve chamber and operated by said abutment and having ports for connecting a local train pipe vent port with one expansion chamber in service and with another expansion chamber in emergency application position and for connecting the vent port to said valve chamber in another position.

11. A triple valve device comprising a movable abutment subject to the opposing pressures of the train pipe and auxiliary reservoir, a main valve operated by said abutment for directly controlling a local emergency train pipe vent port, said piston and valve means having a normal release position and an inner position, and means for opposing the movement of said piston and valve means from the normal release position to the inner position.

12. A triple valve device comprising a movable abutment subject to the opposing pressures of the train pipe and auxiliary reservoir, valve means operated by said abutment and adapted to open a local train pipe

1
vent port in applying the brakes, said valve means being adapted to close the vent port in normal release position and having an inner position in which the port is open to the valve chamber, and means tending to return the valve means from said inner position to normal full release position.

In testimony whereof I have hereunto set my hand.
